ELECTRODE HOLDER

Ford S. Miller, New Salem, Kans.

Application April 23, 1938, Serial No. 203,925

5 Claims. (Cl. 219—8)

The present invention relates to new and useful improvements in electrode holders for electric welding and has for one of its important objects to provide, in a manner as hereinafter set forth, 5 a device of this character embodying novel means whereby an electrode may be rigidly secured in different positions in said device.

Another very important object of the invention is to provide, in an electrode holder comprising a 10 slidable clamping jaw, novel means for actuating and adjusting said jaw.

Other objects of the invention are to provide 15 an electrode holder of the character described which will be comparatively simple in construction, strong, durable, highly efficient and reliable in use, compact, light in weight and which may be manufactured at low cost.

All of the foregoing and still further objects and advantages of the invention will become 20 apparent from a study of the following specification, taken in connection with the accompanying drawing wherein like characters of reference designate corresponding parts throughout the several views, and wherein:

25 Figure 1 is a view in side elevation of an embodiment of the invention.

Figure 2 is a plan view thereof.

Figure 3 is a view in vertical longitudinal section, taken substantially on the line 3—3 of 30 Fig. 2.

Figure 4 is a cross sectional view, taken substantially on the line 4—4 of Fig. 3.

Referring now to the drawing in detail, it will be seen that the embodiment of the invention 35 which has been illustrated comprises a handle 1 of suitable metal, said handle being arcuate in cross section and terminating in a flat forward end portion 2. Mounted on the rear end portion of the handle 1 and projecting therefrom is a 40 tubular grip 3 of suitable insulating material which is secured to said handle, as at 4. Mounted on the flat bar portion 2 of the handle 1 is a metallic bar 5. The bar 5 is secured to the bar portion 2 by a bolt 6 extending therethrough and 45 threaded into a clamp 7 mounted transversely on said bar portion 2. A guide 8 is mounted between the elements 2 and 5 on the bolt 6, said guide also functioning as a spacer for said elements. The bar 5 terminates in an angularly 50 extending rear end portion 9 on which a circular shield 11 of suitable insulating material is mounted, said shield encircling the forward portion of the handle 1, the bar 5, etc.

The reference numeral 12 designates a head in 55 the form of a substantially ovate loop of suitable

metal having its ends secured, as by welding, to the elements 2 and 5 adjacent the forward ends thereof. The loop 12 has formed therein openings 13 for the reception of the usual electrode 14. The electrode 14 may be mounted in the 5 openings 13 in the position shown in full lines in Figs. 2 and 3 of the drawing or, if desired, said electrode may be mounted transversely in the loop 12 as suggested in broken lines in Fig. 2 of the drawing.

Slidably mounted on the guide 8 between the elements 2 and 5 and projecting into the loop 12 for releasably clamping the electrode 14 in position is a substantially flat, metallic jaw 15. Pivotedly mounted at an intermediate point for 15 rocking movement on the rear end portion of the handle 1 is an operating lever 16 for the jaw 15. A cover of insulating material 17 is mounted on the rockable lever 16 and secured thereto, as at 18. The rear portion 19 of the insulating covering 17 is substantially tubular in form and encloses the corresponding portion of the lever 16. The reference numeral 20 designates the hinge which connects the lever 16 to the handle 1. The hinge structure 20 also assists in securing the grip 3 in position on the handle 1. The jaw 15 is operatively connected to the lever 16 for actuation thereby through the medium of a link 21, said link including a turnbuckle 22 for adjustment. Extending through the tubular grip 3 is a 25 conductor 23 for connection with a suitable source of current. The conductor 23 is adapted to rest in the groove or channel defined by the arcuate handle 1. The forward end portion of the conductor 23 is skinned and secured beneath 30 the clamp 7 on the bar 2. It will be noted that the conductor 23 passes through an opening which is provided therefor in the shield 11.

It is thought that the operation of the device 35 will be readily apparent from a consideration of the foregoing. When the rear end of the rockable lever 16 is swung toward the grip 3, the jaw 15 is retracted through the medium of the adjustable link 21. The electrode 14 may then be inserted in the loop 12 either in the position shown in full 40 lines or that indicated in broken lines in Fig. 2 of the drawing. The lever 16 is then rocked in the opposite direction for moving the jaw 15 forwardly into clamping engagement with the electrode 14, as shown to advantage in Fig. 3 of the 45 drawing. When this is done, the pivotal connection 24 between the link 21 and the lever 16 passes dead center for retaining the jaw 15 in 50 clamping position. The turnbuckle 22 permits adjustment of the connection between the jaw 15 55

and the lever 16 to assure proper functioning of said jaw when said lever is swung to the position shown in Fig. 3 of the drawing. The forward ends of the elements 2 and 3 function as scrapers 5 for removing articles of metal that may adhere to the jaw 15. As the conductor 23 is connected to the device at a point adjacent the head or loop 12, the current passes only a short distance through said device and through the heaviest 10 portion thereof. The jaw 15 has formed therein a longitudinal slot 25 (see Fig. 3) which accommodates the guide 8.

It is believed that the many advantages of an electrode holder constructed in accordance with 15 the present invention will be readily understood and although a preferred embodiment of the device is as illustrated and described, it is to be understood that changes in the details of construction and in the combination and arrangement 20 of parts may be resorted to which will fall within the scope of the invention as claimed.

What is claimed is:

1. An electrode holder comprising a pair of spaced metallic bars, a metallic loop, for the 25 reception of an electrode, mounted on one end portion of said bars, a handle on one of the bars, a rockable lever pivotally mounted, at an intermediate point, on said handle, a jaw slidably mounted between the bars, said jaw projecting 30 into the loop and engageable with the electrode in said loop for clamping said electrode in position, and means operatively connecting said jaw to the rockable lever for actuation thereby.

2. An electrode holder comprising a pair of 35 spaced metallic bars, a metallic loop, for the reception of an electrode, mounted on one end portion of said bars, a handle on one of the bars, a rockable lever pivotally mounted, at an intermediate point, on said handle, a jaw slidably mounted 40 between the bars, said jaw projecting into the loop and engageable with the electrode in said loop for clamping said electrode in position, and means operatively connecting said jaw to the rockable lever for actuation thereby, said means 45 comprising a link having one end pivotally connected to the jaw and its other end pivotally connected to the lever, said link including a turn-buckle for adjusting the jaw relative to the lever.

3. An electrode holder comprising a pair of

spaced metallic bars, a metallic loop on one end of the bars for the reception of an electrode, said loop having aligned openings therein for accommodating the electrode, a guide mounted between the bars, a jaw slidably on the guide between the bars, said jaw projecting into the loop and engageable with the electrode in the loop for clamping said electrode in position, a handle on one of the bars, a lever rockably mounted, at an intermediate point, on said handle, and adjustable means operatively connecting the jaw to the rockable lever for actuation thereby.

4. An electrode holder comprising a pair of spaced metallic bars, a guide mounted between said bars, a substantially ovate loop secured to 15 one end portion of the bars, said loop for the reception of an electrode, a jaw slidably mounted on the guide between the bars and engageable with the electrode for releasably clamping same in the loop, said jaw having a slot therein accommodating the guide, a handle on one of the bars, a tubular grip of insulating material mounted on said handle, a conductor passing through the tubular grip, common means for electrically connecting the conductor to the bars and for securing 20 said bars and the guide together, and means for actuating the jaw.

5. An electrode holder comprising a pair of spaced metallic bars, a guide mounted between said bars, a substantially ovate loop secured to 30 one end portion of the bars, said loop for the reception of an electrode, a jaw slidably mounted on the guide between the bars and engageable with the electrode for releasably clamping same in the loop, said jaw having a slot therein 35 accommodating the guide, a handle on one of the bars, a tubular grip of insulating material mounted on said handle, a conductor passing through the tubular grip, common means for electrically connecting the conductor to the bars and for 40 securing said bars and the guide together, and means for actuating the jaw, said actuating means including a lever rockably mounted at an intermediate point on the handle, and a link having one end pivotally connected to the jaw 45 and its other end pivotally connected to one end portion of the lever, said link comprising a turn-buckle for lengthening or shortening said link.
